CONTROL FOR POSITIONING FLOOR CLEAN-
UP DEVICES ON MINING APPARATUSDonald Wiebe, Franklin, Pa., assignor to Joy
Manufacturing Company, Pittsburgh, Pa., a
corporation of Pennsylvania

Application April 27, 1951, Serial No. 223,217

12 Claims. (Cl. 262—28)

1

My invention relates to mining apparatus, and more particularly to the type of mining apparatus which is known as a Continuous Miner. This type of mining apparatus is employed for mining coal or other suitable minerals from a seam or vein without the use of explosives, and for loading out the material removed from the seam or vein as mining progresses.

In a preferred embodiment a Continuous Miner may include a mobile base, such as a tractor base, adapted to travel over a mine floor and carrying a frame which is mounted for horizontal swinging movement relative to the base and having another frame slidably mounted on the swiveled frame for rectilinear movement in radial lines with respect to the axis about which the swiveled frame is turnable. The Miner may further include a vertically swingable disintegrating mechanism extending outwardly from the swiveled frame and carried by the radially slidably frame and desirably including disintegrating elements carried by endless disintegrating chains circulating in similar parallel vertical orbits, and adapted to disintegrate an upright band of coal or other mineral by sumping, swinging and withdrawal movements; and by adjustments of the horizontally swingable swiveled frame the seam or vein may be disintegrated to the desired width. While the disintegrating operation is in progress the disintegrating mechanism may discharge to a material-receiving conveyor and the material delivered to this conveyor may be deposited by the latter in a hopper, from which hopper a suitably laterally, and desirably vertically, adjustable delivery conveyor may deliver the disintegrating material to a desired point. The disintegrating apparatus is provided with means for swinging it in upright planes as well as advancing and retracting it to effect sumping and withdrawal movements.

The foregoing is but illustrative, and modifications are of course possible.

It is important that there be provided as a part of the Miner means for collecting and effecting the discharge of disintegrated material that may fall to the mine floor. A substantial quantity of disintegrated material escapes to the mine floor during the disintegrating operation, and fire hazard, dust explosion hazard, the greater difficulty in setting mine timbers, the loss in actual net tonnage of mineral produced, the increased difficulty in maneuvering the apparatus and maintaining the desired floor and roof levels, and the increased cost of rock dusting are all factors that make effective clean-up important.

2

An object of the present invention is to provide an improved floor clean-up mechanism. Another object of the invention is to provide an improved mining apparatus having improved floor clean-up mechanism associated with it. Yet another object is to provide improved floor clean-up mechanism for a continuous mining apparatus having improved means for accomplishing the efficacious operation thereof. A further object is to provide an improved floor clean-up system for a continuous mining apparatus, which includes disintegrating apparatus and means for successively causing said disintegrating apparatus to effect sumping and shearing operations, which clean-up system includes clean-up devices, means for advancing them with the disintegrating apparatus during sumping, normally advancing them relative to the disintegrating apparatus during sumping, and, if they are not fully advanced relative to the disintegrating apparatus by the end of sumping, automatically providing for further advance relative to the disintegrating apparatus while the latter is performing a shearing operation. Other objects and advantages of the invention will hereinafter appear.

In the accompanying drawings, in which several illustrative embodiments of the invention are shown:

Fig. 1 is a plan view and Fig. 2 is a side elevational view of the forward portion of a Continuous Miner in which the several illustrative embodiments of the invention may be incorporated.

Fig. 3 is an enlarged longitudinal vertical sectional view on the plane of the line 3—3 of Fig. 1.

Fig. 4 is an enlarged transverse vertical view on the plane of the line 4—4 of Fig. 3.

Fig. 5 is a horizontal sectional view, showing details of the sumping and withdrawing mechanism, parts being broken away and the view being taken on the plane of the line 5—5 of Fig. 4, but on a different scale.

Fig. 6 is an enlarged vertical transverse section on the plane of the line 6—6 of Fig. 1.

Fig. 7 is a section on a reduced scale on the plane of the line 7—7 of Fig. 3 showing the front end of the forward material-receiving conveyor and the clean-up devices per se, the latter being shown in their most forwardly swung position.

Fig. 8 is a view similar to Fig. 7, but showing the clean-up devices in relatively retracted position.

Fig. 9 is a transverse sectional view on the plane of the section line 9—9 of Fig. 3, with parts in full.

Fig. 10 is a diagrammatic view showing portions of the hydraulic control system of a Continuous

Miner in which one form of my improved control means is incorporated, only those portions which are of principal interest to the present invention being illustrated in any detail, and parts being broken away to show features of construction.

Fig. 11 is an enlarged section on the plane of the line 11—11 of Fig. 10.

Figs. 12 and 13 are enlarged fragmentary sectional views showing an automatically controlled valve element in two different positions.

Fig. 14 is a diagrammatic view showing portions of the hydraulic control system of a Continuous Miner in which another form of my improved control means is incorporated.

Fig. 15 is an enlarged central section through another form of control valve mechanism.

Figs. 16 and 17 are similar sections, showing the elements of the valve mechanism shown in Fig. 15 in different positions.

Fig. 18 is a transverse section on the plane of the line 18—18 of Fig. 15.

Fig. 19 is an enlarged sectional view showing a slightly different control valve arrangement.

Fig. 20 is a fragmentary diagrammatic view showing portions of the hydraulic control system of a Continuous Miner in which another form of my improved control means is incorporated.

Figs. 21 and 22 are enlarged central sectional views through the control valve illustrated in Fig. 20, these views showing the unitary automatically controlled valve element in two different positions.

It is necessary to describe a certain amount of structure which is not per se original with me in order that the invention may be understood and its setting and arrangement explained.

The mining apparatus within which the invention is incorporated is in many particulars similar to the one disclosed in the John D. Russell application for Continuous Mining Apparatus, Serial No. 139,631, filed January 20, 1950. It includes a mobile support or base 1 having a frame 2, which has swiveled upon it, to swing about an upright axis at 3, a horizontal supporting frame or turntable 4. This turntable has a horizontal portion 5 projecting forwardly in advance of the base 1, and guided on this horizontal frame portion for movement rectilinearly thereon in a radially extending path is a sliding frame or support 6 on which a swingable frame or bar structure 7 is pivotally mounted on a horizontal transverse axis at 8 to swing in vertical planes with respect to the sliding frame. The bar structure 7, of course, also swings horizontally with the swiveled supporting frame or turntable 4 relative to the base 1. The vertically swingable frame or bar structure 7 extends forwardly in advance of the swiveled frame 4 and its pivotal axis 8 is located, when the sliding frame 6 is retracted, a substantial distance in advance of the base. The swingable frame structure 7 carries a mine vein attacking and disintegrating mechanism generally designated 9 for dislodging and disintegrating the coal or other mineral in relatively wide vertical segments from a solid seam or vein. A front loading conveyor 10 on the sliding frame receives the disintegrated material discharged from the vein attacking and disintegrating mechanism 9 and delivers it rearwardly. The specific delivery conveyor structure for receiving material from the front loading conveyor 10 and delivering it to a point at the rear of the machine does not need to be illustrated or described in this application. A full disclosure of a suitable ar-

rangement is contained in the John R. Sibley application, Serial No. 102,996, filed July 3, 1949 and owned by my assignee. The front conveyor 10 extends closely adjacent the mine bottom 5 when the Continuous Miner is in the position shown in Fig. 2, and upwardly and rearwardly, and then horizontally rearwardly to a point of discharge to the delivery conveyor structure mentioned a few lines above. Beneath the rearward portion of the vein attacking and disintegrating mechanism 9, and associated with the front end of the loading conveyor 10 is an improved clean-up mechanism 15, which will shortly be described more fully.

The vein attacking and disintegrating mechanism 9 includes the bar or frame structure 7 about which, as shown, there are guided for orbital movement several parallel endless disintegrating chains 21, each of these being equipped with disintegrating elements 22. The chains are driven by apparatus fully described in other applications of my assignee, including the application of John D. Russell above mentioned, power for the drive of the chains being taken from motors M, M (see Figs. 1 and 2) through appropriate gearing not shown. The right hand motor also drives through appropriate power take-off mechanism 25 the front loading conveyor.

The front loading conveyor 10 and the disintegrating mechanism 9 are adapted to be advanced and retracted with the sliding frame 6 with respect to the turntable 4 by hydraulic feed cylinder and piston mechanisms 39 (see Figs. 4 and 5), to which fluid may be supplied from a suitable source which is shown only in the diagram of Fig. 10.

The disintegrating mechanism 9 may be swung upwardly about its pivot by upswing-effecting mechanism of the hydraulic cylinder and piston operated type. This mechanism forms a portion of the subject matter of the John D. Russell application, Serial No. 139,631, above mentioned, and includes a pair of single acting hydraulic cylinders 32 having bores 33 and arranged with their axes vertical when the disintegrating mechanism is horizontal (see Fig. 2). The cylinders 32 are secured to the sides of the frame or bar structure 7 of the disintegrating mechanism. Downwardly extending brackets 35 are secured to the frame structure of the disintegrating mechanism forwardly of the cylinders 32 and carry pivots 36 for rearwardly extending lever elements or reaction members 37. These lever elements carry brackets 38 pivotally connected by pins 39 to the lower ends of piston rods 40, which are pivotally connected at 41 to suitably packed pistons 42 reciprocable in the cylinder bores 33. The rearward ends of the levers 37 have angularly disposed short arms 43 pivotally connected at 44 to flexible chains 45, which are secured at their other ends as at 46 to the upper portion of the curved front ends 47 of the sliding frame 6, and which are, as it were, draped over the curved frame surfaces as shown in certain of the figures. The cylinders 32 have supply and discharge connections 48 to which fluid is supplied, and from which fluid may be vented, in ways shortly to be explained in connection with the hydraulic diagram of Fig. 10. When fluid is supplied to the cylinders 32 the pistons 42 are forced outwardly in the cylinders. This changes the angle of the levers 37 to the disintegrating mechanism 9 and since the points 70 44 cannot move downwardly, being sustained by

the chains 45, the pivots 36 must necessarily move upwardly and accordingly upswing of the disintegrating mechanism 9 is accomplished upon the admission of fluid to the bores 33 of the cylinders 32. What actually happens is an upward movement of both the cylinders 32 and the pistons 42, with the cylinders rising more rapidly than the pistons and with the pistons 42 higher in the raised position of the disintegrating mechanism than in the lowered position thereof. This arrangement is disclosed in the above mentioned application of John D. Russell.

The front loading conveyor 10 has vertical side plates 51. These at their rear ends support casing elements 52 (Fig. 6) which house bearings 53 in which there are journaled stub shafts 54 which have squared portions 55 to the inside of the side plates 51, and these are connected by their polygonal ends with chain sprockets 56, which are adapted to drive side chains 57 for a purpose later to be described. The side chain driving sprockets 56 have coaxial sleeve portions 59 on each of which there is secured a sleeve member 60, and the aligned sleeve members 60 at their ends adjacent to each other surround and are secured to tubular hub portions 61 of a conveyor chain driving sprocket 62. This cooperates with and drives the center flight conveyor chain 63 of the front loading conveyor 10. Referring to Fig. 6, it will be noted that one of the shafts 54 has an extension 64 to which there is secured at 65 a worm wheel 66, with which a worm 67, mounted in a housing 68 and rotated by the transmission mechanism 25 previously described, engages. It will be understood, accordingly, that the transmission 25 drives the conveyor chain 63 of the front loading conveyor 10 and also drives the pair of drive chains 57, shortly further to be described.

The front loading conveyor has a pivoted front end 70, and the side plates 51 have openings 72 (Fig. 9) in which there are received pivot sleeves 73 which are fixed to the vertical plates 51. These pivot sleeves 73 are surrounded by openings 74 formed in vertical plate portions 75 which form side elements of the pivoted front end 70. These plates 75 have disposed inwardly of them, that is toward the center of the conveyor, parallel plate portions 76. The plate portions 75 and 76 have openings 77 in which bearing portions 78 formed on sleeve-like portions 79 of castings 80 are rotatably received. A split clamp 81 disposed between the plate portions 75 and 76 and surrounding the bearing portions of the castings 80 holds the castings—one at either side—in position with respect to the pivoted front end 70 of the front conveyor. The sleeve portions 79 support bearings 82, in which stub shafts 83 are journaled, and these stub shafts have mounted on their mutually adjacent squared ends sleeves 84, which support an idler roller 85, about which the front end of the conveyor chain 63 is guided. The side plates 51 are connected by a conveyor deck plate 86 and underlying return deck plates 87. The pivoted front end 70 of the front loading conveyor has a deck plate 88 which constitutes an extension of the deck plate 86. The castings 80 are rockable about the axis of the idler roller 85. The pivoted front end 70 and the parts which it supports may be raised and lowered at its front end about the pivots provided at 74. An elevating cylinder 89, supported at 90 beneath the return deck plate 87 and pivotally connected at 91 to the pivoted front end 70, may effect the raising and permit

the lowering mentioned, as hereinafter explained.

The pivoted front end 70 is dished at 92 so that the forward run of the conveyor chain 63 will be partially housed at its bottom end, and suitably beveled surfaces 93, 94 and 95 (see Figs. 7 and 8) are provided at the front end 70 and adapted to rest on the mine floor to guide cuttings or other loose disintegrated material on the floor to the conveyor.

At the inner side of the forward end of the conveyor 10 there are arranged gathering or clean-up devices. These are driven by the side chains 57, which drive sprockets 100 (Figs. 3 and 9) fixedly secured to transversely extending shafts 101 journaled at 102, 102' in sleeve members 103 adjustably secured to the side plates 51 to permit chain tension adjustment. The shafts 101 drive, through Rzeppa universal drive connections 104, telescopic splined drive shafts 105, other Rzeppa universal connections 108, and gearing, not shown, but fully illustrated in said Russell application and enclosed in gear housings 110 carried at the outer ends of clean-up scroll housings 111, clean-up scrolls shortly to be described. Generally semi-cylindrical pick-up plates 113 are pivotally connected as at 114 by multiple hinge connections 115 to lugs 116 on the castings 80. The arrangement is such, noting that the pivotal connections are so formed as to provide a certain amount of free play, that the clean-up devices may swing forwardly and backwardly about generally upright axes and that the upright axes mentioned are turnable about horizontal axes to a limited degree by reason of the fact that the castings 80 are pivotally mounted at 78 as previously explained. The clean-up devices may have universal pivotal connections of any desired form with the castings 80, to obtain the desired pivotal movement.

Each conveyor scroll arrangement includes a rotatable scroll or spiral conveyor in the form of a helix 120. The details of the support and drive of these scrolls need not be here described as they are fully explained in said Russell application. It will suffice to say that the scrolls are rotated in a direction to cause them to move material towards said surfaces 93, 94, 95 and that the scrolls or spiral conveyors can swing backward and forward about an upright axis and can turn—though only to a limited degree as will shortly be explained—about a horizontal transverse axis. The conveyor scrolls have their pick-up plates 113 prevented from undue turning about the pivotal mountings 77, 78, by links 140 pivotally connected to brackets secured to the vertical side plates 51 as illustrated in said Russell application, and as at 142 to the extreme rearward ends of the castings 80.

The gathering or clean-up devices can be swung in and out by double acting hydraulic cylinder and piston mechanisms 150. These include cylinders 151 pivotally connected at 152 to lugs 153 on the castings 80 and having pistons 154 provided with piston rods 155 pivotally connected at 156 to the pick-up plates 113. Fluid may be admitted to the opposite ends of the bores 157 of the cylinders 151 to effect inward and outward swinging of the clean-up devices.

The gathering or clean-up devices are so supported that they will be advanced during sumping of the disintegrating mechanism 9 and retracted during the withdrawal of the disintegrating mechanism. It is desirable that they should advance angularly into the position there-

of shown in Fig. 7 before sumping of the disintegrating mechanism commences and accordingly means is provided for opening a fluid supply connection to them simultaneously with the supply of fluid to the sumping and withdrawal cylinder and piston mechanisms 30. Then, if the resistance to advance of the clean-up devices is such that it requires a lower fluid pressure to effect their advance than is required to sump the disintegrating mechanism, there will be an advance of the clean-up devices before sumping takes place, and in like manner rearward swing of the clean-up devices may provide withdrawal movement of the disintegrating mechanism.

Before going further it may be noted that the cylinder and piston mechanisms 30 are differently constructed. Each includes a cylinder 160 having a bore 161, and there are pistons 162L and 162R reciprocable in the bores. To distinguish them, some further parts of the lefthand (looking forwardly) mechanism 30 will be identified by an L while the righthand ones will be identified by an R. The piston 162L has a piston rod 164L extending forwardly from it and connected to the reciprocable frame 6, and the piston 162R has a piston rod 164R extending forwardly from it and also connected to the reciprocable frame. The piston rod 164L has a passage 165 extending from a point 166 ahead of its associated piston 162L to a point 167 which is never withdrawn into the cylinder even in the most retracted position of the piston 162L, and which has communication with a conduit 170. On the other hand, a passage 171 extends from the rear side of the piston 162R through the latter and through the piston rod 164R to a point 172 which is never withdrawn into the cylinder even in the rearmost position of the piston 162R, and which, at 172, communicates with a conduit 174.

Attention may now be directed to Figure 10, in which the cylinder and piston devices for effecting sumping and withdrawing are shown at 30, the cylinder and piston devices for effecting upswing and lowering of the disintegrating mechanism are shown at 32, 42, and the cylinder and piston devices for angularly advancing and retracting the clean-up device are shown at 150. There will be observed in the lower part of Figure 10, a multiple-unit valve box structure 180. This includes a fluid supply and pressure relief valve unit 181, a discharge unit 182, a control unit 183 for controlling the supply of fluid to, and the venting of fluid from, the cylinder and piston devices 32, 42, a control valve unit 184 for controlling the supply and venting of fluid relative to the sumping and withdrawing devices 30 and the clean-up swinging cylinder and piston devices 150, and a plurality of individually unnumbered units which control other functions of the mining apparatus but which do not in detail enter into the present invention and which therefore need no description. A hydraulic fluid is supplied from a reservoir 186 through a conduit 187 to a pump 188, driven in any suitable manner from one of the motors of the Miner and discharging into a conduit 189, which leads to a chamber 190 in the unit 181. When the relief valve 191 contained in the unit 181 opens, fluid may flow from the chamber 190 through the discharge passage 193 which extends successively through the several valve units to the box 182 and thence by a conduit 195 back to the tank 186. Passage arrangements 197 of well known construction are formed in the various control valve units, and so arranged that when the valve associated with 75 valve 200 of the unit 183 would then be moved

any control valve unit is moved to effect fluid supply, the passage 197 in that unit is closed, but when all of the valves in the control units are in neutral position there is a free flow-through of fluid from the chamber 190 to the return conduit 195.

The unit 183 contains a valve 200 controllable in any suitable manner and adapted, when moved upwardly from the position shown in Fig. 10 to effect fluid supply to a groove 201 which is connected with a conduit 202, and which valve, when moved downwardly from the position shown in Figure 10, connects the conduit 202 with the associated discharge passage 193. The conduit 202 terminates in branches 204, 204, which lead to the bores 33 of the cylinders 32 above the pistons 42 in the latter.

The unit 184 contains a multiple-spool valve element 211, which is adapted when in the position shown in Figures 10 and 11, to effect a supply of fluid to a groove 212 and the venting of fluid from a groove 213, while downward movement from the position shown in Figure 10 to an opposite exterior position will effect fluid supply to the groove 213 and venting of fluid from the groove 212. It will be noted that this valve unit has spaced fluid supply grooves, one, 214, a part of the supply passage arrangement 197 and the other a connected fluid supply groove 215 (see Fig. 11). The groove 212 has connected with it a conduit 216 while the groove 213 has connected with it a conduit 217. Conduit 216 is connected by branches 219, 219 to the rearward ends of the bores 161 of the cylinder and piston devices 32. Conduit 217 is connected by branches 220, 220 to the forward ends of the bores 161. It will be noted that fluid supplied through the conduit 216 and one of the branches 219 will not only act upon the piston 162R, but will also pass to the conduit 174. In like manner, fluid supplied through conduit 217 and one of the branches 220 will not only act in a retraction-effecting direction upon the piston 162L, but will pass to the conduit 170. Conduit 174 is connected by branches 222, 222 to the ends of the cylinder and piston devices 150 wherein it acts to effect scroll retraction. Conduit 174 is connected by branches 224, 224 to the ends of the cylinder and piston devices 150 which are supplied with fluid to effect swinging of the clean-up devices from the position shown in Figure 8 to the position shown in Figure 7.

At this point the description may be discontinued, and the modes of operation which would be accomplished were no other structure provided may be noted: It will be evident that if the valve element 200 is manipulated to allow the venting of fluid from the conduit 202, the disintegrating mechanism 9 may be lowered to floor level and then held at that level by returning the valve 200 to the position shown in Figure 10. The valve 211, previously centered, could then be moved to the position shown in Figure 10 and effect fluid supply to the conduit 216 and venting of fluid from the conduit 217. Then, if the scrolls could be moved forwardly with a lower fluid pressure in the cylinder and piston devices 150 than would be required in the cylinder and piston devices 32 to effect the sumping operation of the disintegrating apparatus, the scrolls would be moved promptly from the position shown in Fig. 8 to the position shown in Fig. 7 and thereafter the cylinder and piston devices 30 would effect sumping of the disintegrating apparatus 9. The

to supply fluid to the conduit 202, and this fluid, acting in the cylinders 32 would effect upswing of the disintegrating apparatus 9. The movement of the valve 200 as described would interrupt communication between the supply groove 214 and the supply chamber 190. This would mean no more fluid could be delivered to the branches 224, 224 to effect further forward swing of the clean-up devices. When the desired limit of upswing was attained, the valve 200 would be returned to the position shown in Fig. 10, and the disintegrating mechanism would be locked in its raised position. Fluid would then be supplied, by downward shifting of the valve 211, to the conduit 217, and this fluid would, if rearward swinging (swinging from the position of Figure 7 to the position of Figure 8) of the clean-up devices could be accompanied with lower pressure than that needed to effect withdrawal, would cause the clean-up device to swing back before withdrawal took place, and withdrawal would thereafter be immediately effected.

With the arrangement so far described it will be evident that if, for some reason, the clean-up devices did not attain to the position of Fig. 7 before sumping was completed, and the valve 200 was shifted to effect upswing of the disintegrating apparatus, complete advance of the clean-up devices will not be effected.

My invention provides a further opportunity for the completion of the advancing movement of the clean-up device from the position of Figure 8 to the position of Figure 7. This it does by providing for the continued supply of fluid to the cylinder and piston devices 150 during upswing of the disintegrating apparatus. Several novel arrangements by which this may be accomplished without undesirable concomitants will now be described, and the first of these is illustrated in Figs. 10 to 13, both inclusive.

It will be observed, noting now particularly Figs. 10, 12 and 13, that I have provided a shuttle valve device 230 including the casing 231 having extending longitudinally thereof a larger bore 232 and a communicating coaxial smaller bore 233. An annular stop shoulder and seat 234 is formed at the end of the bore 232 remote from the bore 233, and this shoulder surrounds a passage 235 of smaller diameter than the bore 232. With this passage a conduit 236 communicates. Its connections will shortly be described. An annular shoulder or seat 238 is arranged at the junction of the bores 232 and 233. The bore 233 is connected with a conduit 239, whose connections will shortly be described. A lateral passage 240 opens into the larger bore 232 approximately midway between its ends, as shown. This has a conduit 241 communicating with it, and the latter is connected to one of the branch conduits 224. A valve element 245, including a portion 246 of larger diameter and a connected portion 247 of smaller diameter, is arranged within the bores 232 and 233, the portion 246 being a close sliding fit for the bore 232 and the portion 247 a close sliding fit for the bore 233. The valve element 245 has a conical end 249 remote from its smaller portion 247, and this end is adapted to seat upon the shoulder or seat 234, which is correspondingly frusto-conically formed. A frusto-conical shoulder 250 is formed at the junction of the valve portions 246 and 247, and annular shoulder 238 is made frusto-conical to provide a seat for the shoulder 250. The valve 245 is traversed by an L-shaped passage, including a portion 252 opening through the side of the larger portion 246 at 75

253. The other portion, 255, of the L-shaped passage extends axially of the valve and opens through the end of the reduced portion 247 at 256. In order that rotation of the valve on its axis 5 may not interfere with its functioning, there is provided an annular groove 258 in communication with the passage 240.

The conduit 236 connects with one of the branches 222. The conduit 239 is provided with 10 a check valve 260, and is connected at its end away from the valve device 230 with the conduit 202. The valve 260 permits fluid to pass through the conduit 239 from conduit 202 towards the valve device 230, but prevents its opposite flow. 15 The conduit 241 opens into one of the branches 224.

The space in the larger bore 232 at the end of the latter nearer the smaller bore 233 will desirably have a bleed 262, and this may advantageously be connected by conduit means (not 20 shown) with the tank 186, if there is any material leakage.

Now the operation of the apparatus, with the valve of Figs. 12 and 13 incorporated in it as 25 shown in Fig. 10, may be briefly described. When fluid is being supplied to effect sumping of the disintegrating apparatus 9, the valve 245 will normally occupy the position shown in Fig. 12. If it did not initially fully do so, it would be promptly

30 moved to this position, because fluid moving through the L-shaped passages 252, 255 could not escape past the check valve 260, and as any space above the valve 245 would be vented, during sumping, to the tank 186, the valve 245 would be 35 moved to the position mentioned by the pressure which would pass to the lower end of the smaller portion 247. In either event it will be evident that no fluid could pass from the conduit 174, one of the branches 224, and the conduit 241 in 40 any substantial amount. Therefore, when the valve 211 is in the position of Figs. 10 and 11, fluid will be supplied through conduit 216 and the branches 219 to the cylinder and piston mechanisms 30, and effect sumping of the disintegrating apparatus, and some of this fluid will pass through the passage 171 and conduit 174 and branches 224 to effect outward and forward swing of the clean-up devices. Meanwhile, the forward ends of the cylinder and piston devices 30 45 and the other ends of the cylinder and piston devices 150 would be vented to the tank 186 through the conduit 211. If the resistance to forward movement of the clean-up devices is not too great, they will make their full shift from the position of 50 Fig. 8 to the position of Fig. 7 before sumping starts, or at least before sumping is completed. But if they do not, for any reason, complete their movement from the position of Fig. 8 to that of Fig. 7, before sumping is completed, the operator 55 can simply maintain the valve 211 in the position shown in Figs. 10 and 11 and move the valve 200 to supply fluid to the conduit 202. Most of the fluid supplied through the conduit 202 will pass into the cylinder bores 33 and effect upswing of the disintegrating apparatus, but a portion of this fluid will pass into the conduit 239 and, having opened the check valve 260, will be delivered into the bore 233, and, passing through the passage in the valve 245, will be delivered to the passage 240 and through the conduit 241 to one of the branches 224, and from that branch to the other branch 224, and thus there will be a 60 continued application of force to the pistons 154, to effect forward swing of the clean-up devices, during upswing of the disintegrating mechanism.

With the valve 211 held as specified, none of the fluid attaining to conduit 241 can escape through the conduit 174, passage 171, communicating branch 219, and conduit 216. It will also be noted that the ends of the cylinder and piston devices 150 which are connected by the branches 222 will continue to be connected with the tank 186. Thus, every opportunity will be provided, during upswing of the disintegrating mechanism, for the clean-up devices to make their full movement from the position of Fig. 7, if they have not previously made it.

At the end of upswing of the disintegrating mechanism the valve 200 will be returned to the position shown in Fig. 10, shutting off supply of fluid to the conduit 202 and trapping fluid in the cylinder bores 33. The valve 211 will then be moved to its opposite position and will supply fluid to the conduit 217 while venting the conduit 216. Fluid supplied to the conduit 217 will be delivered to the retracting end of the cylinder and piston devices 30 and 150, while the other ends of the cylinder and piston devices 30 and 150 are connected to the tank. The clean-up devices may be swung backward before withdrawal takes place or during a withdrawal, depending upon the relative resistances to movement. Because the pressure acting in the branches 222 will act through the conduit 236 on the materially larger end 249 of the valve 245, the valve will be forced to its position shown in Fig. 13, and accordingly the fluid within the conduit 202 cannot be vented through the conduit 241, the conduit 174, etc.

At the end of retraction of the disintegrating mechanism, the valve 211 may be moved to its neutral position and the valve 200 moved to vent fluid through the conduit 202 from the cylinder bore 33 to permit downswing of the disintegrating mechanism. Under these circumstances the valve 245 will remain in the position of Fig. 13, notwithstanding pressure in the conduit 239, because fluid above the upper end of the valve cannot escape, since the valve 211 closes conduit 236.

When the valve 200 is returned to neutral position (when the disintegrating mechanism is lowered as far as desired), there will either be a pressure in the conduit 202, or one will be produced there the instant the disintegrating mechanism starts to cut a clearance, and thus the valve 245 will normally be moved to the position of Fig. 12 by the time sumping is commenced.

To summarize, it may be stated that the valve mechanism 230 makes possible the application of a continued force, tending to swing the scrolls to their position of Fig. 7, throughout upswing of the disintegrating apparatus, as well as during sumping movement of this mechanism. It is necessary to maintain the valve 211 in its sumping-effecting position during upswing of the disintegrating mechanism in order for continued forward movement of the scrolls from the position of Fig. 8 to that of Fig. 7 to take place during upswing, for only thus is venting of the piston rod ends of the cylinder and piston devices 150 possible. The check valve 260 guards, during sumping, against flow of pressure fluid into the shear cylinders from the lines supplied with pressure during sumping.

Now turning to Figs. 14 to 18 it will be observed that I have omitted the check valve 260 in the conduit 239 and provided a modified form of valve mechanism 271 which performs the functions of the check valve 260 and of the shuttle

valve device 230. Some parts are not shown in detail in Fig. 14, as they are fully shown in corresponding parts of Fig. 10; and like numbers are used in Fig. 14 in cases where corresponding parts appear in Fig. 10. It may be noted that, in view of the absence of the check valve 260, the conduit which otherwise corresponds to the conduit 239 of Fig. 10 is designated 239' in Fig. 14.

The valve mechanism 271 includes a casing 275 having a cylindrical bore 276 provided with a transverse shoulder 277 at one end surrounding a connection at 278 for the conduit 236. The other end of the bore 276 terminates in an annular valve seat 280 surrounding a passage 281 with which the conduit 239' communicates. As shown, substantially midway between the ends of the casing 275, there is a connection 283 for the conduit 241. This connection communicates with an internal groove 284. Within the bore 276 and adapted to cooperate with the seat 280, there is a check valve element 285 having an annular seating surface 286 adapted to cooperate with the seat 280 and traversed by a series of longitudinally extending peripheral grooves 287. Accordingly, when the valve 285 is unseated, there is established communication between the conduit 239' and the conduit 241. A spring loaded plunger 290 is received in the bore 276 above the check valve element 285, and it has a projection 291 of reduced diameter which is adapted to engage an end surface 292 on the check valve 285, under certain conditions. The length of the plunger is such that under no conditions can the communication of the connection 283 with the bore 276 be interrupted. A spring 293 is enclosed within the bore 276 and engages a transverse surface 294 on the follower member 290, and also engages the annular shoulder 277. When there is no pressure in any of the conduits 236, 239' and 241, the check valve element 285 and the plunger 290 occupy the position shown in Fig. 17. When there is pressure in the conduit 241 tending to cause fluid flow toward the conduit 239', the parts occupy the position of Fig. 15. When there is, in the conduit 239', pressure which must pass to the conduit 241 and effect complete extension or forward movement of the scrolls, the position of the parts may be as shown in Fig. 16.

The operation of the apparatus of Figs. 14 to 18 inclusive is as follows:

When fluid is being supplied to effect sumping of the disintegrating apparatus 9 the position of the parts of the device 275 will be that shown in Fig. 15. This will be understood when it is borne in mind that at this time the conduit 236 is vented to the tank 186 and the valve 285 will have been moved to the position shown in Fig. 15, as soon as the pressure in the conduit 241 exceeded the pressure in the conduit 239'. Accordingly, none of the fluid supplied to effect forward swing of the clean-up devices during sumping will act in the cylinder bores 33 to raise the disintegrating apparatus.

At the end of sumping, there will be a shift of the valve 200 to supply fluid to the elevating cylinder and piston devices 32, 42, while the sump controlling valve 211 remains in its sump-effecting position. Thus fluid supplied to the conduit 202 will flow to the cylinder and piston devices 32, 42, and also, in part, to the conduit 239', and this fluid will then pass the check valve 285 and pass to the conduit 241 and continue the forward swinging action of the clean-up devices, and thus every opportunity will be provided, during upswing of the disintegrating mechanism, for the

clean-up devices to make their full potential movement to the position of Fig. 7, if they have not previously made it.

At the end of upswing of the disintegrating mechanism the valve 200 will be returned to the position shown in Fig. 10, shutting off supply of fluid to conduit 202 and trapping fluid in the cylinder bores 33. The valve 211 will then be moved to supply fluid to the conduit 217 and vent the conduit 246. The fluid supplied to the conduit 217 will in part ultimately pass to the conduit 170 and to the retracting ends of the cylinder and piston devices 150. Whether or not the clean-up devices will swing back before, during or after retraction of the disintegrating apparatus will depend upon the resistances to movement involved. Because the pressure acting through the conduit 236 on the end of the plunger 290 will exceed any pressure tending to unseat check valve 285, and because, moreover, of the force exerted by the spring 293, the parts will move to the position shown in Fig. 17, and accordingly the fluid within the conduit 202 will not be vented through conduit 239', the conduit 241, the conduit 174, etc. It will be understood that the present embodiment of the invention will function essentially, so far as controls accomplished are concerned, like the first form.

Figure 19 shows another arrangement which could be used in place of the arrangement of Figs. 15, 16 and 17. The sole difference is that the spring 293' is arranged between the plunger 290 and the check valve 285. It will be understood that with respect to the valve arrangements of Figs. 14 to 19, the strength of the springs 293 and 293' need not be great.

The modification of Figs. 20, 21 and 22 needs even less extended description. Fig. 20 is a diagrammatic view, and, as it is a part of a system which is identical with that of Fig. 14 except that the conduit 236 has been omitted and that a valve mechanism 301 of different form has been substituted for the valve mechanism 271, it has been possible to omit a large part of what is shown in Fig. 14. The valve mechanism 301 includes a casing 303 having a cylinder bore 304 closed at one end, as at 305, except for a vent 306 and for a valve seat 307 at its other end surrounding a passage 309 with which the conduit 239' communicates. A check valve 311 is received in the bore 304. It is herein in the form of a cylindrical plug having a frusto-conical seat 312 at its lower end and having a transverse upper surface 313 engaged by a spring 314 of which the other end rests against the surface 305. When the check valve is seated by the spring 314 it shuts off communication between an annular groove 316 formed in the wall surrounding the bore 304, and the passage 309. The groove 316 is connected by a passage 317 with the conduit 241.

Except when the disintegrating apparatus 9, is resting on a lower motion limiting device, not shown, it will, unless it is being swung upwardly (where the fluid pressure will naturally be higher), exert a certain pressure on the fluid in the bores 33. This pressure obviously varies depending upon the design of the apparatus, but let it be assumed, for example, that it is on the order of a 150 p. s. i. and let it also be assumed that when the valve 311 lifts from its seat there is an increase in area subject to fluid pressure supplied through the conduit 239' of one-third. This will mean that, to move valve 311 from the position shown in Fig. 22 to that shown in Fig. 21, if the conduits 241 and 239' were both shut off 75

from the tank, the spring 314 would have to exert a pressure in excess of 200# to move the valve from the position of Fig. 22 to that of Fig. 21. Sound design principles would result in making the spring exert a substantially higher pressure—one on the order of 300 p. s. i. over the area of the lower end of the valve when unseated. Now note that when the valve is in the position of Fig. 22 and fluid is passed from the conduit 239' to the conduit 241, there is no material reduction in the pressure in the conduit 241 from that in the conduit 239'.

The mode of operation may be readily visualized. It will be appreciated that the pressure supplied to the conduit 202 to effect the shearing operation will also in part act in the cylinder and piston devices 150 to complete the forward and outward swing of clean-up devices. When the valve 200 is moved to neutral position, the valve 211 will also be moved to neutral position, and then there will be fluid trapped within the rear ends of the bores 33, the branches 204, the conduit 202, the conduit 239', the space beneath the valve device 311, the conduit 241, branch connections 224 and the space within the cylinders 154, the conduit 174, the passage 171, the rear ends of the cylinders 160 and the connecting branches 219 and the conduit 246. As the spring 314 exerts pressure which is greater than the product of the cross-sectional area of the valve 311 and the entrapped fluid mentioned, the valve 311 will be moved from the position of Fig. 22 to the position of Fig. 21, and the valve will maintain that position even during the next forward sumping operation because there will be nothing to displace it. Of course, since the conduit 236 is omitted in this embodiment of the invention, the spring 314 provides the only force for moving the valve 311 from the position of Fig. 22 to that of Fig. 21, but that force is more than adequate when such movement is required, but yet such as to be readily overcome by the pressure supplied to effect shearing.

While there are in this application specifically described several forms which the invention may assume in practice, it will be understood that these forms of the same are shown for purposes of illustration and that the invention may be modified and embodied in various other forms without departing from its spirit or the scope of the appended claims.

What I claim and desire to secure by Letters Patent is:

1. In combination, a frame advanceable and retractable with respect to a mine floor, pressure fluid operated mechanism for effecting such movements of said frame, vein disintegrating mechanism mounted on said frame for movements in upright planes relative thereto, pressure fluid operated mechanism for effecting upward movement of said disintegrating mechanism in said planes, floor clean-up devices supported by said frame and having pressure fluid operated mechanism for advancing and retracting them relative to said frame and to the mine floor, means for effecting fluid supply and exhaust of fluid relative to said first mentioned pressure fluid operated mechanism and relative to said third mentioned pressure fluid operated mechanism to effect concurrent advance of said frame and clean-up devices and to effect concurrent retraction of said frame and of said clean-up devices, said means including, for effecting such retraction, conduit means for supplying fluid for effecting retraction and, for effect-

15

ing advance, other conduit means for supplying fluid to effect advance means including an operator controllable valve mechanism and a conduit controlled thereby for selectively supplying pressure fluid to and venting pressure fluid from said second mentioned pressure fluid operated mechanism, and means, including a valve controlled conduit connecting said last recited conduit with the conduit means for supplying fluid to effect advance of said frame and said clean-up devices, for effecting supply of fluid to such conduit means from said last recited conduit automatically upon supply of pressure fluid to said second mentioned pressure fluid operated mechanism but precluding flow to the latter through said valve controlled conduit.

2. The combination of claim 1, in which the valve controlled conduit has therein a valve movable to flow-permitting position by fluid flowing from the conduit connected with said second mentioned pressure fluid operated means towards the conduit means for supplying fluid to effect advance.

3. The combination of claim 2, in which the valve movable to flow-permitting position by fluid flowing from the conduit connected with the second mentioned pressure fluid operated means towards the conduit means for supplying fluid to effect advance has associated with it means for moving it to flow-interrupting position automatically upon cessation of the flow of fluid which moves it to flow-permitting position.

4. The combination of claim 2, in which the valve movable to flow-permitting position by fluid flowing from the conduit connected with said second mentioned fluid operated means towards the conduit means for supplying fluid to effect advance has a pressure fluid actuated plunger associated with it for moving it to flow-interrupting position under the action of fluid pressure in the conduit means for supplying fluid for effecting retraction.

5. The combination of claim 4 in which the valve having associated with it a plunger also has a spring associated with it for biasing it in the same direction said plunger acts.

6. The combination of claim 2, in which the valve movable to flow-permitting position by fluid flowing from the conduit connected with the second mentioned pressure fluid operated means towards the conduit means for supplying fluid to effect advance has a spring associated with it for moving it to flow-interrupting position automatically upon cessation of the flow of fluid which moves it to flow-permitting position.

7. The combination of claim 1, in which the valve controlled conduit has therein a check valve openable toward the conduits to effect advance.

16

8. The combination of claim 1, in which the valve controlled conduit has a plurality of valves between its ends each openable by fluid passing toward said conduit means for supplying fluid to effect advance, and one having associated with it means for closing it, subjected to the pressure in the conduit means for supplying fluid for effecting retraction.

9. The combination of claim 1, in which the valve controlled conduit has therein a valve openable by fluid supply toward said conduit means for supplying fluid to effect advance, and said valve has associated with it a closing plunger subjected to the pressure in the conduit means for supplying fluid for effecting retraction and in which said plunger has its movements by said last mentioned pressure spring-opposed.

10. In combination, a frame reciprocable with respect to a mine floor, pressure fluid operated mechanism for effecting such reciprocation, vein disintegrating mechanism mounted on said frame for movement in upright planes relative thereto, pressure fluid operated mechanism for effecting upward movement of said disintegrating mechanism in said planes, floor clean-up devices supported by said frame and having means including pressure fluid operated mechanism for advancing and retracting them relative to said frame and to the mine floor, means for effecting fluid supply and exhaust relative to said first mentioned pressure fluid operated mechanism to effect advance and retraction of said frame, means for effecting fluid supply and exhaust relative to said third mentioned pressure fluid operated mechanism including conduits for supplying fluid to effect advance and conduits for supplying fluid to effect retraction of said clean-up devices, means for supplying and venting fluid with respect to said second mentioned pressure fluid operated mechanism including a conduit connected with the latter, and means for automatically supplying fluid from said last recited conduit, upon the supply of pressure fluid thereto, to the conduits for supplying fluid to effect advance of said clean-up devices, but precluding reverse flow including a valve movable by pressure fluid supplied to said last recited conduit.

11. The combination of claim 10, in which said valve is subjected in opposite directions to pressures which exist respectively in the last recited conduit and in the conduits for supplying fluid to effect retraction of said clean-up device.

12. The combination of claim 10 in which the valve is a check valve.
